United States Patent Office

Des. 220,658
Patented May 4, 1971

220,658

REAR PROJECTION VIEWER

William K. Christoffersen, North Minneapolis, James L. Keely, Wayzata, William T. Owens, Jr., Long Lake, and Larry D. Quanrud, North Minneapolis, Minn., assignors to Washington Scientific Industries, Inc., Long Lake, Minn.

Filed May 21, 1970, Ser. No. 23,091

Term of patent 14 years

Int. Cl. D16—04

U.S. Cl. D61—1

FIG 1

FIG 2

FIG 3

FIG 4

FIG 5

FIG 6

FIG. 1 is a front side perspective view of a rear projector viewer, showing our new design;

FIG. 2 is a front elevational view thereof;

FIG. 3 is a right side elevational view thereof;

FIG. 4 is a left side elevational view thereof;

FIG. 5 is a top elevational view thereof; and

FIG. 6 is a back elevational view thereof.

We claim:

The ornamental design for a rear projection viewer, as shown.
